UNITED STATES PATENT OFFICE

HAROLD T. ACKERMAN, OF DETROIT, MICHIGAN, ASSIGNOR, BY DIRECT AND MESNE ASSIGNMENTS, TO HIMSELF, AND JESSE W. MATTESON, AND ENOCH PROUTY, BOTH OF HIGHLAND PARK, MICHIGAN

TRUCK AND BUS IDENTIFYING LIGHT

Application filed May 26, 1927. Serial No. 194,402.

The object of the invention is to provide a simple, cheap, and yet effective construction of device for use on trucks or busses where the municipal regulations require the display of a plurality of lights of distinguishing color; to provide a construction wherein the effect of a plural display is secured by the employment of a single light; and to provide a construction wherein the support of the light is such that it will be maintained intact, irrespective of the jars to which such devices are subjected.

With this object in view the invention consists in a construction and combination of parts of which a preferred embodiment is illustrated in the accompanying drawings, wherein:

Figure 1 is a front elevational view of the invention.

Figure 2 is a longitudinal horizontal sectional view on the plane indicated by the line 2—2 of Figure 1.

Figures 3 and 4 are transverse vertical sectional views on the planes indicated by the lines 3—3 and 4—4 of Figure 1.

The casing or housing 10 is made preferably of plate metal of comparatively heavy gauge and comprises the two sections 10^a and 10^b, the former being formed to provide the rear wall 11 and the top and bottom walls 12 and 13, the flanges 14 being inturned from the top and bottom walls and serving as a means for securing the section 10^b in place. The section 10^b comprises the front wall 15 and end wall 16 and the means for securement of the two sections together consist of screws 17 passing through body holes in the front wall of the section 10^b and threadingly engaging tapped holes in the flanges 14, lock washers 18 being interposed between the heads of the screws and the front wall 15 to prevent recession of the screws.

The top and back walls 12 and 11 extend beyond the ends of the front and bottom walls 45 to provide attachment brackets 19 at either end of the casing, in which attachment brackets are formed fastener holes 20.

In the front wall 15 there are formed the 50 openings 21 uniformly spaced along the front wall and directly behind the latter is

a light penetrable panel 22 of the color prescribed by the regulations under which the device is used. The panel 22 is disposed behind the flanges 14 and at each end is spanned by cushions 23 of felt or some other acceptable material which is interposed between the flanges and the panel and serves as a means to prevent breakage of the latter. The panel is retained in place by the flanges 24 which abut it on its inner face and which span the top and bottom flanges 14 at the ends of the latter, fasteners 25 extending through the flanges 14 and 24 and securing the two together. The flanges 24 are integral parts of bracket plates 26 which are disposed at approximately forty-five degree angles at opposite ends of the casing and interiorly of the latter and serve as a means for the support of the mirrors 27 which are secured in place thereon by pliable lips 28 carried by the brackets. In addition to the flanges 24, the brackets are provided with foot or base flanges 29 resting upon the bottom wall 13 and secured to the latter by means of fasteners 30. The brackets 26 are disposed directly behind the end openings 21 in the front wall and behind the center opening is disposed the illuminating medium in the form of a lamp 31 removably mounted in a socket 32 carried at the upper extremity of a coil spring 33, the latter being secured to a base plate 34 which is in turn secured to the bottom wall 13 of the casing by means of bolts or fasteners 35.

In the bottom wall 13 of the casing is formed an opening 36 closed by a removable plate 37 secured in place by detachable fasteners 38.

The spring 33 serves as a support for the lamp and is of a gauge of wire sufficient to maintain it normally upright and to support the weight of the lamp. It constitutes, however, a flexible support for the lamp so that the latter is not likely to be damaged by jolting or jarring of the truck on which the device is used. When the lamp is lit, the light rays shine directly through the center opening 21 and are reflected through the end openings by the mirrors 27 disposed directly behind those openings. Thus the effect of 100

three lights is secured with but the use of one.

Should access to the casing be necessary, it may be had by the removal of the plate 37 which would readily permit the replacement of a burnt out lamp through the opening 36. The whole device may be dismantled by the disengagement of the screws 17 and the bolts 25 which will permit the removal of the section 10^b and also the removal of the light penetrable panel 22. The mirror bracket may be dismantled if desired by the removal of the bolts 30 and similarly the lamp bracket may be dismantled by the removal of the bolts 35.

The invention having been described, what is claimed as new and useful is:

1. A device for the purpose indicated comprising a casing formed of sheet metal and consisting of a duality of sections of which one comprises the back, top and bottom walls and the other the front and end walls, the first said section at the longitudinal edges of the top and bottom walls being formed with inturned flanges, and fasteners extending through the front wall and engaging said flanges to secure the two sections together.

2. A device for the purpose indicated comprising a casing composed of two sections of which one is formed with back, top and bottom walls and inturned flanges at the edges of the top and bottom walls and the other is composed of front and end walls, fasteners extending through the front wall of the second section and engaging the flanges of the first section, a light penetrable panel disposed behind said flanges, and members spanning said panel at its opposite extremities and provided with means for securing them to the flanges of said top and bottom walls.

3. A device for the purpose indicated comprising a casing having an opening formed in the front wall thereof, an illuminating member disposed behind said opening, and a laterally yieldable and longitudinally expandable and compressible support for said member.

4. A device for the purpose indicated comprising a casing having an opening formed in the front wall thereof, an illuminating member disposed behind said opening, and a flexible support for said member consisting of a helical spring secured at one end to the member and anchored to the casing at said other end.

In testimony whereof he affixes his signature.

HAROLD T. ACKERMAN.
